UNITED STATES PATENT OFFICE.

MELVIN L. SEVERY AND MIKARL SCUTERUD, OF ARLINGTON HEIGHTS, MASSACHUSETTS, ASSIGNORS TO SEVERY MANUFACTURING COMPANY, OF BOSTON, MASSACHUSETTS, A CORPORATION OF MASSACHUSETTS.

POWER-TRANSMISSION MECHANISM.

1,126,102.

Specification of Letters Patent.

Patented Jan. 26, 1915.

Application filed January 25, 1913. Serial No. 744,166.

To all whom it may concern:

Be it known that we, MELVIN L. SEVERY and MIKARL SCUTERUD, both of Arlington Heights, in the county of Middlesex and State of Massachusetts, have invented certain new and useful Improvements in Power-Transmission Mechanism, of which the following is a specification.

This invention relates to an improvement in power transmission mechanism.

The object of the invention is to provide a reversible, variable-speed mechanism, which also performs the functions of a system of leverages by increasing the torque and decreasing the speed.

The invention comprises a double driving member, a driven member, and an interposed fluid, the latter being throttled or impeded in its circulation through the device to vary the speed of the driven member.

In the accompanying drawings Figure 1 is a central, vertical longitudinal section of an illustrative embodiment of the invention, Fig. 2 is a transverse vertical section taken on the line 2—2 in Fig. 1, the conical annulus being shown in elevation and Fig. 3 is a similar view taken on the line 3—3 in Fig. 1.

As illustrated in the drawing, the device comprises a cylindrical drum composed of sections 10 and 12, bolted together and having substantially flat outer end walls 14, 16, respectively, the drum 10 also having an inner end wall 18, open at the center. The cylindrical wall of the drum is provided with a filling hole closed by a screw 20, and a vent to be opened during the filling but normally closed by a screw 20^a similar to the screw 20. The end wall 14 is provided with a stuffing-box 22, through which a hollow boss 24 passes, said boss having a stuffing-box 26 at its outer end and being slidably mounted on the section 28 of a driving or crank-shaft. The crank-shaft is constructed of two sections 28 and 29, the section 28 having a groove 30 on its inner end adapted to receive a tongue 31 formed on the adjacent end of the section 29, and this joint is held in place by a collar 32. The outer end of the shaft-section 29 is slidably mounted in a cylindrical cavity 34 formed in a boss 36 on the end wall 16, said boss being affixed to a driven shaft 38. The

driving shaft 28, 29 does not move longitudinally, whereas the driven shaft 38 is 55 slidable longitudinally, the boss 36 being slidable over the section 29 of the driving shaft, and the boss 24 being slidable over the section 28, said bosses being provided with grooves 40, 41, respectively, adapted to receive shipper rods. The end 29 of the crank-shaft is provided with a vent 44 which communicates with the cavity 34 to prevent the trapping of any fluid in said cavity.

The section 28 of the crank-shaft is provided with a crank-pin 46, shown in Fig. 2, to which a plurality of piston rods 48 are connected. Although three piston rods are shown, it will be understood that any number may be employed. The piston rods 48 are connected to pistons 50, slidable in cylinders or holes 52 formed in a conical disk 54. The disk 54 is formed with an axial boss 56 rotatable on the crank-shaft section 28, and the periphery of said disk is formed 75 with an internal gear 58. Both ends of the cylinders or holes 52 are open, and the conical surface of the disk 54 forms the engaging surface of the inner member of a friction clutch. The outer member of the 80 clutch is a cup-shaped member 60, having a conical inner surface adapted to fit the conical surface on the disk 54, and to fit over and close the outer ends of the holes 52. The clutch-member 60 is formed integrally 85 with or is affixed to the boss 24, and is accordingly slidable along the shaft 28, being keyed to said shaft by a key 62, which is slidable in a key-way 64 in said shaft. The section 29 of the crank-shaft is also provided with a crank-pin, to which a plurality of piston rods 66 are connected.

The rods 66 are connected to pistons 68, slidable in cylinders or holes 70, formed in an annulus 72 having an outer conical surface. This annulus forms the inner member of a friction clutch and is provided with an annular rib 74, which is joined to a similar rib 76 on the side of an external gear 78, said gear having a boss 79 journaled to rotate on the boss 56. The annulus 72 is secured to the gear 78 by pins or screws 80 passing through said annulus and through the ribs 74 and 76. The external gear 78 meshes with a plurality of pinions 82 journaled on stud-shafts 83 mounted in the wall

18 of the drum, and said pinions also mesh with the internal gear 58. Both ends of the cylinders or holes 70 are open, and the conical outer periphery of the annulus 72 is 5 adapted to fit the correspondingly shaped inner surface of a cup-shaped clutch-member 84. The clutch-member 84 is slidably keyed to the driving or crank-shaft section 29 by a key 86 slidable in a keyway 88 in 10 said shaft, and said member is rotatably fastened to the end wall 16 by a plate 90 which engages an annular shoulder formed on said member. The entire space within the drum is filled with a fluid 92, which may 15 be oil, glycerin, or any other suitable substance.

When the fluid 92 is allowed to pass freely into and out of the cylinders there is no motion of the driven end or shaft; but when 20 the outer clutch-members, which also serve as valves to more or less close the outer ends of said cylinders, are moved by their shippers toward their respective inner complementary clutch-members, then the flow of 25 fluid through the cylinders is impeded and the pistons react upon the cranks and tend to tie the crank-shaft and piston-member together. When said outer clutch-members close the cylinders entirely the clutch-members, being splined to the driving-shaft, take 30 the full load, while at the same time their complete impedance to the flow of the fluid causes a complete locking of the crank-shaft and cylinder members together. When the 35 parts are thus locked together the gears 58, 78, and 82 have no relative rotation and the drum and driven shaft rotate at the same speed as the driving shaft.

If either or both of the valve members is 40 moved back to allow a completely free flow into and out of the cylinders, the shaft 38 will not be driven by the shaft 28 except that there may exist a slight driving tendency due to the friction of the parts of the 45 device and the friction of any liquid flow. If both the valve members are moved toward the cylinder members to throttle the flow into and out of the cylinder, or if one valve member be moved over into positive driving 50 engagement with its cylinder member while the other valve member is moved over to throttle the flow into and out of its corresponding cylinder member, then the shaft 38 will be driven at reduced speed from the 55 shaft 28, the speed of the member 38 tending to increase as the clutches increase the throttling action, and this speed finally becomes identical with the speed of the driving shaft 28 when both valve members have entered 60 into a positive frictional driving engagement with their corresponding cylinder members. The device thus provides means to give a wide range of speed reduction which is subject to close regulation.

The specific construction of the clutch device used herein forms the subject matter of our copending application, Serial No. 738,526, filed December 26, 1912, and accordingly is not claimed herein. 65

What we claim is:—

1. The combination of a pair of axially aligned and independently rotatable shafts; a planet gear mounted to revolve with one of said shafts; a pair of gears rotatably mounted on the second shaft coaxial therewith and meshing with opposite sides of said planet gear; a pair of clutches of the fluid type, each adapted to clutch said second shaft to a corresponding one of the two gears mounted thereon to provide a variable 80 speed-reducing drive between the same; and means for individually controlling the action of said clutches. 70

2. The combination of a pair of axially aligned and independently rotatable shafts; a planet gear carried by one of said shafts to revolve therewith; a pair of gears rotatably mounted on the second of said shafts coaxially therewith and meshing with opposite sides of said planet gear; cone clutch members operatively connected one with each of the gears on said second shaft and each formed with a plurality of cylinder spaces having their ends terminating on the clutch surfaces of said clutch members; pistons in said cylinders; crank connections between said pistons and said second shaft; co-acting cone clutch members splined on said second shaft and shiftable to engage the clutch surfaces of said first named cone 95 clutch members and adapted as they approach their engaging positions to throttle the flow of fluid into and out of said cylinder spaces; means for shifting said clutch members independently of each other; a 100 suitable casing structure inclosing said clutch members; and a liquid confined by said casing. 90

3. The combination of a pair of axially aligned and independently rotatable shafts; a planet gear carried by one of said shafts; a pair of gears rotatably mounted on the second of said shafts and meshing with opposite sides of said planet gear; variable speed driving connections between each of said 110 gears and said second shaft; and means for controlling said variable speed driving connections to vary the speed ratio between said shaft and gears. 115

4. The combination of a pair of axially aligned and independently rotatable shafts; a planet gear mounted on one of said shafts to revolve as the same rotates; an orbit gear and a sun gear rotatably mounted on said second shaft; pump mechanisms one associated with the orbit gear and the other associated with the sun gear, each adapted to produce a circulation of fluid by the rela- 120 125

tive rotation of said second shaft with reference to the corresponding gear; and combined clutch and valve mechanisms one for each pump mechanism, and each adapted
5 first to throttle the flow of said liquid and then to enter into mechanical clutching engagement with the corresponding gear.

In testimony whereof we have affixed our signatures, in presence of two witnesses.
